Primary Examiner — Elizabeth J Oswecki(74) *Attorney, Agent, or Firm* — ScienBiziP, P.C.(57) **CLAIM**

The ornamental design for a shoe, as shown and described.

DESCRIPTION

FIG. 1 is a front, left, and top perspective view of a shoe, showing my new design.

FIG. 2 is a rear, right, and bottom perspective view thereof.

FIG. 3 is a top plan view thereof.

FIG. 4 is a bottom plan view thereof.

FIG. 5 is a left side elevation view thereof.

FIG. 6 is a right side elevation view thereof.

FIG. 7 is a front elevation view thereof.

FIG. 8 is a rear elevation view thereof.

FIG. 9 is an enlarged portion view labeled, “FIG. 9,” in FIG. 7; and,

FIG. 10 is an enlarged portion view labeled, “FIG. 10,” in FIG. 8.

The even broken lines shown in the drawings are included for the purpose of illustrating portions of a shoe that form no part of the claimed design. The dashed-dot broken lines show the boundary of the enlarged portion views of FIGS. 9 and 10 in FIGS. 7, 8, 9 and 10.
